UNITED STATES PATENT OFFICE.

GEORGE C. WEISS, OF OAKLAND, CALIFORNIA.

MACHINE ELEMENT.

1,386,037.

Specification of Letters Patent.

Patented Aug. 2, 1921.

Application filed July 16, 1920. Serial No. 396,682.

To all whom it may concern:

Be it known that I, GEORGE C. WEISS, a citizen of the United States, residing in Oakland, in the county of Alameda and State 5 of California, have invented a new and useful Improvement in Machine Elements, of which the following is a specification.

The present invention relates in general to a combination of machine elements and 10 has reference more particularly to an improved mechanical movement for realizing a so-called compound tumbling or revolving motion.

As an illustrative embodiment I have selected a washing machine as an example of reducing the invention to practice; however, its use is in no way confined to such machines as it may also find expression in various other devices—for instance: in cement mixers, churns, and different kinds of 20 tumblers.

In the accompanying drawing, Figure 1 is a plan view of a washing machine, cement or the like mixer, illustrating the application 25 of the invention, and Fig. 2 is a side elevation of the same.

Referring to the drawing in detail: the principle involved primarily consists in effecting a compound revolving or tumbling 30 movement for the container 5, which may be of any desirable shape and construction to which end I propose to support the container by the standards 6 and 7 with bearings 8 and 9 arranged thereon in each of 35 which is mounted a short shaft or axle. Co-axially mounted upon the shaft in the bearing 9 is a driving element represented by the pulley 10 which is adapted to be connected in driving relation with a suitable 40 power medium for driving the machine. Each of the shafts referred to will be fixed in driving relation to a frame 11 comprising a mounting for the container which may be of any suitable construction and arrangement.

Fixed to the bearing 8 is a beveled gear 12 which is made to mesh with a like gear 13 carried by the frame 11 and fixed upon the sleeve 14 which loosely surrounds the 50 part 15 of the frame 11 with the beveled gear 16 mounted upon the opposite end of the sleeve and made to mesh with another beveled gear 17 carried on an adjacent side of the frame 11 and fixed upon the sleeve 55 18 which loosely surrounds the part 19 of

the frame with still another beveled gear 20 mounted upon its opposite end.

Arranged in the opposite sides of the container 5 and extending outwardly therefrom are the shafts 21 and 22 which are supported in suitable bearings 23 and 24 carried by the frame 11 so that the container 5 is free to rotate with its axis of rotation arranged to intersect the axis of rotation of the frame 11. Carried upon and fixed to the shaft 60 22 and made to mesh with the gear 20 is a bevel gear 25, which completes the driving means for rotating the container.

From the above description it will be seen that the frame 11 may be rotated in a fixed 70 orbit and when thus rotated, a rotating motion will also be imparted to the container 5 through the gear arrangement—consequently, a common driving means will impart a compound revolving or tumbling motion to the container. It will be revolved with the frame and in the same direction at the same time the gears will impart an independent rotation to the same with its axis of rotation intersecting the axis of rotation of the frame.

In lieu of the gear arrangement shown and described, a chain drive may be provided by changing the gears 16 and 25 to sprocket wheels and connecting the same in 80 driving relation by sprocket chains.

I claim:

1. In combination, a rotatable element, a rotatable mounting therefor, comprising a skeleton frame having a rotatable bearing 90 on two opposite sides, a support for the mounting arranged to support said rotatable bearings, direct driving means for rotating the mounting in a fixed orbit with the container carried thereby, a driving gear co-axially mounted upon and fixed to a transverse part of said mounting, a driven gear carried upon one side member of said skeleton frame and adapted to mesh with said driving gear, a second driven gear mounted upon said side member of the frame adapted to be driven by said first named driven gear and adapted to mesh with a gear carried upon another side member of the frame, said last named gear adapted to drive a gear 105 mounted co-axially thereof and in driving relation to a gear carried upon and in driving relation with the element; whereby the rotation of the mounting is adapted to also rotate the element in a fixed orbit independ- 110

ent of the mounting and with its axis of rotation intersecting the axis of rotation of the mounting.

2. In combination, a four sided skeleton frame, said frame including horizontal rotatable shafts arranged on opposite sides of the frame, bearings in which said shafts are free to rotate, means mounted upon one of said shafts comprising a driven element for revolving the frame, an element mount-

ed within the frame and having shafts on its opposite sides mounted free to rotate in bearings in the frame and driving means between the frame and the element whereby the rotation of the frame is adapted to ¹⁵ also rotate the element with its axis of rotation intersecting the axis of rotation of the mounting.

GEORGE C. WEISS.
